UNITED STATES PATENT OFFICE.

JOHN GILL, OF EDINBURGH, SCOTLAND.

BLAST-FURNACE AND MEANS FOR OPERATING THE SAME.

SPECIFICATION forming part of Letters Patent No. 470,481, dated March 8, 1892.

Application filed April 14, 1890. Serial No. 347,881. (No model.)

To all whom it may concern:

Be it known that I, JOHN GILL, gentleman, a subject of the Queen of Great Britain, residing at 2 Heriot Row, Edinburgh, in the county 5 of Mid-Lothian and Kingdom of Great Britain, have invented certain new and useful Improvements Connected with Blast-Furnaces, of which the following is a specification.

This invention relates to improvements in 10 blast-furnaces for the smelting of ores, minerals, metals, and other materials, and in gas-producers and tuyeres connected therewith. The blast-furnace is to be closed at the top and to have the usual cup and cone or other 15 suitable arrangement for charging ore and fuel. Reductive gases, especially hydrogen and carbon oxide, may be prepared by a gas-producing furnace, as hereinafter described, and are to be admitted or forced at a suitable 20 temperature into the blast-furnace near the top, whence they descend through the ores and fuel in the upper part of the furnace, and the whole or part of the descending gases are then drawn off through an opening or series 25 of openings around the furnace and are conducted down to the tuyeres near the bottom. The tuyeres each consist of an outer and inner tuyere, with an annular ring or space between them. A pressure air-blast is forced 30 through the inner tuyere into the blast-furnace, and the inflammable gases brought down from the upper part of the furnace enter the annular ring or space between each inner and outer tuyere, and the nozzle of the 35 outer tuyere projects beyond the nozzle of the inner tuyere, and is so formed that the pressure air-blast passing through the inner tuyere draws or forces into the furnace along with itself a supply of the said inflammable gases. 40 The air-blast and those inflammable gases mix and ignite inside the furnace, and their combustion intensifies the heat, increases the fusing power, quickens the action of the furnace, and enables it to be worked with less 45 fuel, less air-blast, and with other advantages. The supply of air-blast and of gases admitted by the tuyeres may be regulated or controlled by means of stop-cocks or valves or similar appliances on the pipes or conduits conveying them to the tuyeres. The air-blast may be cold or hot; but hot blast is preferable, especially in large furnaces. The waste gases

or products of combustion ascend from the zone of fusion through the materials in the furnace and pass out by an opening or series 55 of openings around the furnace at a height some distance below the point where the gases in the upper part of the furnace are taken off. The waste gases and products of combustion after passing out of the furnace, as above 60 mentioned, enter a chamber immediately outside the furnace, in which chamber there is or may be placed a gas-producing furnace closed at top by a cup and cone or other suitable arrangement for charging it with fuel. 65 The waste gases surround the gas-producing furnace and give up to it part of their sensible heat. The gas-producing furnace may be made of cast metal or other suitable material. The heat of the waste gases may also be used 70 for heating the air-blast and for raising and superheating steam. Those gases may pass off partly or wholly by a chimney or partly or wholly by a down-comer. Part may go by a down-comer and be used for heating the air- 75 blast or for raising steam or for other purposes, and only part may enter the chamber in which the gas-producing furnace is placed, and may there be burned, with the addition of air-blast, to increase the heat of that chamber. 80 The gas-producing furnace has an opening in it whereby the gases produced therein pass off by a conduit or pipe and enter the blast-furnace by one or more openings near the top. Such opening in the gas-producing 85 furnace is preferably placed near the bottom. Tuyeres for the admission of air-blast are placed at various heights, or, at all events, near the bottom of the gas-producing furnace, and also at some distance under the level of 90 the top of the fuel in the said furnace. Each tuyere can be shut off by means of a stop-cock. When the fuel in the gas-producing furnace is kindled and brought to a red heat by means of the air-blast through the tuyeres 95 at the bottom, the air-blast is then shut off from those tuyeres and turned on by the upper tuyeres, and then the products of combustion pass downward through the red-hot fuel and out by the opening near the bottom 100 above mentioned and enter the blast-furnace near the top, as already stated. As the only outlet for the gases produced in the gas-producing furnace is by the opening leading into

the blast-furnace, those gases are under sufficient pressure to enable them to force their way down through the materials in the upper part of the blast-furnace. Sufficient air-blast is admitted to keep the fuel under the tuyeres in the gas-producing furnace at a bright red heat, and superheated steam in limited quantity is admitted a short distance under the level of the upper tuyeres. The result is a continuous conversion of the superheated steam into hydrogen and carbon oxide. In some cases the heat of the waste gases issuing from the blast-furnace may be sufficient to keep the fuel within the gas-producing furnace at a sufficient heat for the continuous formation of the requisite quantity of gases from superheated steam, in which case the air-blast for the gas-producing furnace may be shut off. The gas-producing furnace may also be worked with air-blast and without the admission of any steam. The quantity of gas to be produced by the gas-producing furnace can be regulated as required by admitting more or less air-blast and more or less superheated steam, and the temperature of the gases produced can also be regulated in like manner. Coke, coal, slack, dross, or any kind of fuel may be used both in the gas-producing furnace and also in the blast-furnace. Either hot or cold air-blast may be used for the gas-producing furnace; but hot blast is preferred. At the bottom of the gas-producing furnace the ashes may be drawn off by a revolving screw or other suitable means. The chamber in which the gas-producing furnace is placed can also be used, if desired, for placing therein a coil of pipe for heating the air-blast. The reductive gases formed by the gas-producing furnace and entering the blast-furnace near the top at a proper temperature heat up the contents of the upper part of the blast-furnace to the requisite temperature and distill the volatile portions of the coke, coal, or any raw fuel that may be used therein, turn the moisture in the ores and fuel into gases, and carry down all the gases formed there through the ores and fuel in the upper part of the furnace, which gases, containing hydrogen and carbon oxide and being kept at a suitable temperature by the regulation of the heat in the gas-producing furnace, have a powerful effect in preparing and reducing the ores. The admission of those gases from the gas-producing furnace and their combustion at the tuyeres, as above described, enable the blast-furnace to be worked with less than the usual amount of air-blast and to be charged with less than the usual amount of fuel, and to be worked with coke, coal, wood, or other raw fuel, and so that all the volatile portions of such fuel will be utilized in the furnace, in the first place in reducing the ores and secondly for increasing and intensifying the fusing power of the furnace. In some instances it may be desired to dispense with the gas-producing furnace, but to adapt the drawing down to the tuyeres of the gases

in the upper part of the furnace, and in such cases a supply of hot gases for the top of the furnace may be got by making an opening 70 a few feet above the tuyeres, and conducting the gases issuing therefrom by a conduit to the top of the furnace. The conduit can be made of suitable size, and can be regulated by a valve or other means so as to carry 75 such a supply of hot gases as shall sufficiently heat up the contents of the upper part of the furnace and no more. According to these arrangements the furnace is divided into two parts, an upper and a lower. In the upper 80 part the gases descend and in the lower they ascend toward the outlet for the waste gases, which is placed at the division between the upper and the lower part of the furnace. The lower part of the furnace can be increased or 85 diminished in height and the upper part can be diminished or increased in height to suit the requirements of the material to be smelted. The hot furnace-gases to be drawn down to the tuyeres may in some cases be taken 90 from any short distance above the tuyeres where they have a high temperature. The adoption of this part of the invention may be of advantage by itself to any ordinary furnace. It is desirable to follow this course 95 where it is desired to allow all the gases descending in the upper part of the furnace to pass out of the furnace in order to carry off impurities, which otherwise might enter the metal or regulus. The arrangements 100 described will have advantages in enabling small concentrates and the dust of ores to be smelted without the loss which frequently takes place by the dust of the ores and fuel being blown out at the top. Any dust of ores escaping 105 from the blast-furnace, as above described, can be deposited in a catch-pool and made to flow into the hopper at the top of the furnace. The arrangements described also afford facilities for eliminating impurities from ores, &c., 110 in the upper part of the blast-furnace before the ores reach the zone of fusion. In such cases the reductive gases, admitted near the top of the blast-furnace, are allowed to descend and to leave the furnace along with the 115 waste gases arising from the zone of fusion, without any portion of them being drawn off and burned at the tuyeres; but a supply of the reductive inflammable gases may be taken direct from the gas-producing furnace to the 120 tuyeres at the bottom of the blast-furnace without passing through the upper part of the blast-furnace, or otherwise a supply of inflammable furnace-gases may be drawn down to the tuyeres from an opening or openings 125 a short distance above the tuyeres and below the outlet for the waste gases. In furnaces for smelting such ores, where it is desirable to prevent impurities therein from entering the regulus or metal, it may be desirable to have the outlet for the products of combustion at a short distance above the zone of fusion and to have the upper part of the furnace above such outlet made higher. 130

Where it is desired to carry off impurities both from the upper part of the furnace and also from the lower part, the upper part may be worked by means of reductive gases from a gas-producing furnace and the lower part by the air-blast through the tuyeres with or without the addition of inflammable gases drawn either from the gas-producing furnace or from a short distance above the tuyeres. By the arrangements described the heat in the upper as well as in the lower part of the blast-furnace is under the control of the furnaceman. He can increase it or diminish it at pleasure either in the lower or upper part of the furnace, and as the reductive gases necessary in the upper part of the furnace can be supplied in sufficient quantity either from the gas-producing furnace or by a conduit from the lower part of the furnace, and gaseous fuel can also be obtained at the zone of fusion in sufficient quantity to produce the heat necessary there, the fuel to be mixed with the ores and charged into the blast-furnace need not be more or much more than is required for the chemical reactions in the two parts of the blast-furnace. The fuel used both in the gas-producing furnace and also in the blast-furnace is consumed, especially when the waste gases issuing from the blast-furnace are burned for heating air-blast, raising and superheating steam, or for heating a reverberatory furnace, so that the entire heat which the fuel is capable of producing is developed and utilized. In any case the fuel can be so consumed that very little of its heating power is lost, and there is also much additional reductive and fusing power got from the hydrogen brought into the furnace. The use of hydrogen in the blast-furnace as being one of the most effective reductive and heating agents known will be of some value, and the arrangements described will enable it to be applied with great advantages. In the drawings, Figures 1, 2, 3, and 4 are vertical sections of blast-furnaces adapted for the purposes of carrying out my invention.

Fig. 1 shows a close-topped iron-smelting blast-furnace A A', with a close-topped gas-producing furnace B in an adjoining chamber C. The blast-furnace has an upper part A and a lower part A' and an outlet D for the waste gases between them. This outlet D communicates with an opening or recess E, made round the inside of the brick-work of the furnace. The waste gases on passing out of the furnace surround the gas-producing furnace B and then leave the chamber C by a down-comer F, to be used for heating the air-blast and for raising steam. The gas from the gas-producing furnace B is conducted by a pipe or passage G to near the top of the blast-furnace, where it enters and passes round in a channel H, made in the brick-work, whence it passes through openings H' into the furnace; or it may pass direct from the pipe or passage G into the recess H², made

round the inside of the brick-work of the furnace. It then passes down through the ores and fuel in the upper part of the furnace till the whole or part of it is drawn off by a recess I, made round the brick-work and communicating with a passage J, which leads it to a channel K, whence it is drawn down through passages K' by and to the tuyeres L, to be mixed with the air-blast entering the furnace and burned therewith inside the furnace.

In the arrangement shown in Fig. 2 the gas-producing furnace is dispensed with and a supply of hot gases is taken by a recess M made round the inside of the brick-work and an opening N in communication therewith a short distance above the tuyeres and conducted by a conduit G, built in fire-brick, to near the top of the furnace, where it enters at H' into a recess H², made round the inside of the brick-work of the furnace, and it then descends through the materials in the upper part of the furnace till the whole or part of it is drawn off at I and conducted down by the conduit J to the channel K, whence it is led by passages K' to the tuyeres L to be mixed with the air-blast entering the furnace. The descending of the gases in the upper part of the furnace is caused or promoted, first, by the pressure of the gases in the lower part of the furnace; second, the suction or exhaustion in the conduit J, leading down to the tuyeres, caused by the force of the pressure air-blast through the tuyeres, and, third, the draft of the chimney acting through the outlet F for the waste gases. The opening N in the lower part of the furnace for the gases going to the top of the furnace may be much nearer to the tuyeres than is shown in the drawings. In this arrangement hot-air blast and superheated steam may be introduced into the upper part of the furnace for the purpose of forming hydrogen and carbon oxide to aid the reductive action of the furnace, and also to aid the fusing action at the tuyeres.

Fig. 3 shows a furnace, which may be a water-jacket furnace, for smelting copper ores, concentrates, &c. The gases descend in the upper and rise in the lower part of the furnace. There is a passage N, about two feet above the tuyeres, communicating with a conduit G, which opens into the furnace at H', near the top thereof. This conduit G takes a regulated supply of hot furnace-gases to the top of the furnace. These gases and the volatile portions of the fuel descend through the upper portion of the furnace, and the whole or part thereof is then drawn off by a conduit J, leading to the tuyeres L, in a manner similar to that described in reference to Fig. 2. The waste gases pass off at F, about half-way up the furnace, to the chimney R. There is a catch-pool S in the chimney for collecting flue-dust and allowing it to run into the hopper T on the top of the furnace, whence it enters the furnace with each successive charge.

Coal or coke or any kind of fuel may be used with this furnace.

Fig. 4 is a diagram showing how a series of my improved blast-furnaces may be combined and worked together and may be so arranged as to volatilize and carry off some impurities from the ores or fuel in the upper parts of such furnaces. According to this arrangement the gas-producing furnace delivers its hot gases into the upper part of the first blast-furnace of the series at preferably somewhat under the surface of the ores or materials in the furnace. They pass down through the ores and fuel in the said upper part, and after heating, reducing, and preparing the said ores are led off wholly or partly at V to waste or to heat the gas-producing furnace or to be utilized for other heating purposes. The furnace-gases from the lower part of the furnace are taken off at E, wholly or in part, and are conducted by the passage or conduit D to the upper part of the second blast-furnace in the series. These gases, after passing down through and heating, reducing, and preparing the ores in the upper part of the said second blast-furnace are taken off at W and are led away by the passage or conduit F', either to waste or to be utilized for heating purposes. The furnace-gases from the lower part of the said second furnace are taken off wholly or partly at E^x, and are conducted by the passage or conduit D^x to the upper part of the third blast-furnace in the series, and so on for any required number of blast-furnaces. The gases introduced into the upper part of the last furnace in the series, after passing down through the ores and fuel and heating, reducing, and preparing the ores in the upper part of such furnace, are taken off at E^{xx} along with the gases from the lower part of the furnace, and are led away by the passage or conduit F² to waste or to be utilized for heating purposes.

The outlets V and W for the waste gases coming from the upper parts of the first and second furnaces are preferably restricted by means of suitable dampers or otherwise, so as to maintain the pressure of the gases in the lower part of each of those furnaces, respectively, and thereby to force such gases into and down through the upper part of the next furnace in order.

When it is desired to volatilize or remove impurities from the ores by a preliminary operation of roasting or calcining them before they enter the blast-furnace, a series of two furnaces may be combined, the second of which is used as a roasting or calcining furnace in which the ores are placed without the addition of any fuel, and the first is used as a blast-furnace, consisting of upper and lower parts, as above described, and the upper part is worked by means of gases from a gas-producing furnace, as already described. These gases on leaving the upper part of the blast-furnace, with or without the addition of part of the furnace-gases from the lower part of the blast-furnace, are conducted to the upper

part of the second or calcining furnace, where they enter and pass down through the ores in the upper part thereof, and thence go to waste, while the furnace-gases from the lower part of the blast-furnace or part thereof are conducted to the lower part of the second or calcining furnace, where they enter and ascend through the ores in the lower part thereof, and thence go to waste. By this arrangement the ores are subjected to several successive currents of hot gases, first, in the upper part of the second or calcining furnace; second, in the lower part thereof; third, in the upper part of the first or blast furnace, and, fourth, in the lower part thereof. The admission of superheated steam and air blast into the upper and lower parts of the second or calcining furnace, either continuously or intermittently, 85 may be of much advantage.

I am aware that it is not new to provide an escape for the waste gases from a blast-furnace located in a position between the upper and lower portions of such furnace; also, that it is not new to admit an air-blast at or near the top of a blast-furnace, so as to produce a descending current therein; also, that it is not new to employ a gas-producing furnace for supplying gases to be mixed with the air-blast at or near the tuyeres of a blast-furnace; but, so far as I am aware, a gas-producing furnace has not hitherto been used for supplying gases, especially hydrogen, to the upper part of a blast-furnace for the reduction of ores in such upper part.

I am also aware that it is not new *per se* to draw off furnace-gases near the top and to bring them down and mix them with the air-blast at the tuyeres, and I would have it understood that I make no claim separately to any of the features above stated to be not new; but

What I do claim is—

1. The process of reducing ores mixed with fuel and arranged in a vertical column, which consists in igniting the fuel, thereby causing inflammable gases to be evolved, drawing off these gases from the lower portion of the column, introducing them into the upper part of the column, and causing them to descend through the column, substantially as set forth.

2. The process of reducing ores, which consists in arranging the ore in furnaces in several vertical columns, causing a blast of reducing gases to pass downward through the first of the series of columns of ore, conducting the gases which escape from this furnace to the top of the next in the series, causing such gases to pass downward through the column of ore in such furnace, and so on throughout the series, substantially as set forth.

3. The herein-described method of operating blast-furnaces, consisting in supplying inflammable gases to the upper part of the furnace, in causing said gases to pass down through the material to be reduced, in then withdrawing them from the furnace, together with other gases which may have been taken

up or acquired from said material, and in then forcing the gases so withdrawn into the bottom of the furnace, together with an air-blast, substantially as set forth.

- 5 4. The herein-described method of operating blast-furnaces, consisting in supplying inflammable gases to the upper part of the furnace, in causing said gases to pass down through the material to be reduced, in then withdrawing them from the furnace, together with other gases which may have been taken up or acquired from said material, in then forcing the gases so withdrawn into the bottom of the furnace, together with an air-blast, 10 and in withdrawing the products of combustion from the furnace at a height intermediate between the point of exit of said gases and the point of their reintroduction, substantially as set forth.
- 15 5. The herein-described method of operating a blast-furnace, which consists in causing a current of hot inflammable gases to descend through the upper part thereof, withdrawing hot furnace-gases from the lower portion of 20 the furnace and above the tuyeres, forcing or

blowing said furnace-gases, with the air-blast, into the bottom of the furnace, and withdrawing the products of combustion at a point below the exit of said furnace-gases, substantially as set forth.

30 6. The herein-described blast-furnace, having the duct G communicating with a gas-generator opening into the top of the furnace, the duct J in the outer wall, the distributing surrounding duct K, the ducts K', connected therewith, and the air-blast tuyeres at the lower end of the latter duct, substantially as set forth.

35 7. A blast-furnace having a gas-opening H', communicating with a gas-generator, and exit I, communicating with the tuyeres, and an outlet-flue for the products of combustion intermediate between said exit I and the tuyeres, substantially as set forth.
